UNITED STATES PATENT OFFICE

ARTHUR F. NELSON, OF HARRISBURG, PENNSYLVANIA

CHANGE MAKER

Application filed February 4, 1927. Serial No. 165,810.

This invention relates to improvements in change making devices provided with means for carrying coins and means operable to discharge coins from the carrying means.

5 An object of the invention is to provide a change maker of novel, inexpensive and efficient construction wherein the coins may be caused to fall from the device more nearly in a vertical direction, and wherein the 10 coins may be inverted and stacked one upon another in the hand of the user of the device as the coins are discharged from the device.

Another object of the invention is to 15 eliminate the use of screws, bolts, nuts and rivets in securing the parts of the device together.

Another object of the invention is to improve the several elements of the frame 20 structure and coin ejecting mechanism of the device whereby advantages not heretofore present are gained.

The invention resides in the elements and the combinations of them hereinafter 25 described and claimed.

Figure 1 is a top view of a change maker embodying my invention.

Figure 2 is a front view thereof.

Figure 3 is a bottom view thereof.

30 Figure 4 is a vertical section of the device on line 4—4 of Fig. 1.

Figure 5 is a vertical section of the device on line 5—5 of Fig. 1.

35 Figure 6 is a vertical section of the device on line 6—6 of Fig. 4.

Figure 7 is a sectional detail of a portion of the frame structure showing one of the coin ejecting members on the base plate.

40 Figure 8 is a sectional detail showing the manner of connecting one of the coin tubes to the rear wall of the frame structure.

Figure 9 is a rear view of a portion of the device.

45 Figure 10 is a perspective view of one of the levers for operating one of the coin ejecting members.

Figure 11 is a perspective view of one of the coin ejecting members.

50 Figure 12 is a perspective view of one of

the bifurcated springs for operating one of the coin ejecting members.

Figure 13 is a rear view of one of the coin tubes.

Figure 14 is a side view of one of the 55 coin tubes.

Referring to the drawings, the frame structure of the device comprises a bent sheet metal member 2 and a series of vertically-disposed, spaced tubes 3 of varying sizes adapted to receive and carry coins of varying diameters. The sheet metal member 2, as herein illustrated, is formed of a single piece of material and it comprises a top plate 7, a bottom plate 8 and a rear plate 9 connecting the top and bottom plates. The forward portion of the top plate 7 is provided with semi-circular cut-out portions to conform to the several tubes 3 and to form bearings for the tubes against 70 the plate.

Each tube 3 is formed of a single piece of sheet metal having a downwardly extending lug 10 formed on the central forward portion thereof and two parallel lugs 11 extending rearwardly from the rearward portion of the tube in spaced relation to each other and in spaced relation to the top and the bottom of the tube. The rear plate 9 of the frame structure has a forwardly pressed, horizontally extending indentation 12 therein; and the lugs 11 of each tube extend therefrom to the indentation 12 in the rear wall 9. The rearward ends of the lugs 11 have shoulders 13 formed thereon which engage the indentation of the rear wall 9, and the lugs 11 have lips or projections 14 which extend rearwardly from the shoulders 13 through openings in the wall 9 and which are bent over into engagement with the rearward surface of the wall 9 within the indentation 12 therein to connect the lugs 11 to the wall. 85

The downwardly extending lug 10 of each tube 3 is provided with shoulders 15 spaced 90 below the bottom of the tube a distance equal to or slightly in excess of the thickness of the coins adapted to be carried by the tube, and the shoulders 15 engage the top of the base plate 8 to retain the bottom of the tube in the 100

proper spaced relation to the top of the plate 8. Each lug 10 is provided with a lip or projection 16 which extends downwardly from the shoulders 15 and through an opening in the base plate 8 and which is bent over into engagement with the bottom of the plate 8 to connect the bottom of the tube to the base plate.

Thus it will be understood that the tubes 3 are firmly and rigidly connected to the frame member 2 in a manner to cause the frame member to stiffen the tubes and the tubes to stiffen the frame member.

The base plate 8 is provided with coin discharging openings 17, one for each tube 3, which correspond in size with the interiors of their respective tubes, and which have their centers located rearwardly of the centers of their respective tubes. These openings 17 are each provided with a coin interrupting part or shelf 18 which is formed integral with the base plate 8. Each part or shelf 18 extends below the level of the body of the plate 18 and beneath the rearward portion of its opening 17 in close proximity thereto; and each part or shelf 18 is constructed to be encountered by the rearward portion or side of each coin discharged through its opening 17, during its descent therefrom, for a purpose hereinafter explained.

The base plate 8 forms a support for stacks of coins within the tubes 3. The stacks of coins rest upon the base plate 8 and the lowermost coin of each stack is free to be moved rearwardly over the plate 8 and beneath its tube 3, and the coins above it to the discharge opening 17 back of the tube. When the bottom coin of a stack is thus moved rearwardly, the coins above it are prevented from moving with it by the rearward wall of the tube 3 containing them.

I shall now describe the mechanism which is operable to move the coins from the tubes to the discharging openings 17, one such mechanism being provided for each tube.

Slidable on the base plate 8 and beneath the tubes 3 are coin ejectors 19, one for each tube, and each comprising a bottom part or plate 20 having a coin receiving opening 21 therein, a top part 22 spaced above and extending over the bottom plate 20 and a rear part 23 connecting the top and bottom parts 20, and 22, all being formed of a single piece of sheet metal, as clearly shown in Fig. 11.

These ejectors 19 are adapted to slide rearwardly and forwardly on the base plate 8 and the sides of the bottom plates 20 of the ejectors are guided by and between walls which project upwardly from the base plate 8 and which are formed integral therewith. The walls which guide the outer sides of the end ejector plates 20 are formed by upturned flanges 24 on the ends of the base plate 8, and the walls which guide the inner sides of the end ejector plates 20 and the sides of the in-

termediate ejector plates 20 are formed by upwardly pressed indentations 25 in the base plate 8.

Upward displacement of the ejectors 19 are prevented by lugs 26 formed integral with the tubes 3 and projecting outwardly from the sides of the lower ends thereof directly above the sides of the ejector plates 20.

Each ejector plate 20 rests normally in the forward position with its opening 21 in registry with the tube 3 above it to receive a coin therefrom, as shown by full lines in Fig. 5, and when it is moved to this position its further forward movement is stopped by the top part 22 of the ejector engaging the back of its coin tube 3.

The forward end portion of each ejector plate 20 is cut out, at 27, to permit each plate 20 to clear the connecting lug 10 of its tube 3 when the plate 20 is moved rearwardly to the position shown by dot-and-dash lines in Fig. 5; and the width of the opening 27 of each plate is less than the diameter of the coins to be ejected by the plate, so that, when each ejector plate 20 is moved rearwardly from the position shown by full lines to the position shown by dot-and-dash lines in Fig. 5, it will move the coin resting within its opening 21 from its tube 3 to and discharge it through the discharging opening 17 back of its tube.

The coin ejectors 19 are adapted to be operated by levers 28, one for each ejector. Each lever 28 is formed of a single piece of sheet metal, as clearly shown in Fig. 10, comprising two spaced ejector operating arms or members 29 connected by a part 30, and a hand operated arm 31 projecting forwardly from one of the ejector operating arms 29.

The upper end portions of the arms 29 of the levers 28 are fulcrumed on pins 32 which extend through the same and through the lugs 11 of the coin tubes 3, one lever 28 being fulcrumed on the lugs 11 of each tube, and the lower end portions of the arms 29 of each lever 28 extend into openings 33 in the top part 22 of the underlying coin ejector 19. The hand operated arm 31 of each lever 28 extends around one side of its coin tube 3 with its forward free end portion terminating in a convenient position to receive the thumb of the person using the device when it is in service.

Each coin ejector 19 is pressed normally forward with its top part 22 engaging the back of its coin tube 3, by a bifurcated spring 34 formed of a single piece of flat, resilient metal and constructed as clearly shown in Fig. 12, and comprising a horizontal top plate or part 35 and two spaced, parallel arms 36 extending downwardly therefrom. The connecting member or plate 35 of each spring 34 engages the lower surface of the upper frame plate 7 and it is secured thereto by means of a securing part or strip of metal 130

37 (Figs. 1 and 5) which extends around the bottom of the plate 35 and embraces the same and has its end portions extended up through openings in the top frame plate 7 and bent over the same, as shown in Fig. 5. The top plate 35 of each spring 34 is provided with a projection 38 which extends up through the top frame plate 7 and is bent over the same with one end portion of its connecting part or strip 37. The lower end portions of the 10 spring arms 36 bear against the backs of the lower end portions of the side arms or members 29 of the operating levers 28 to restore them and their coin ejectors 19 to the normal position shown by full lines in Fig. 5, after they have been moved therefrom and released by the depression and release of the hand operated arms 31 of the levers 28.

It will now be understood that if coins be placed within each tube 3, the stacks of coins will rest therein supported by the base plate 8 with the lowermost coins of the stacks within the openings 21 of the coin ejectors, and that each time a hand operated arm 31 is depressed the lowermost coin within the tube 3 governed by the arm will be ejected from the device by being moved rearwardly beneath the tube to and discharged by gravity through the opening 17 in the base plate 8 rearwardly of the tube 3.

During the operation of the change maker, the person using the same places his right hand in front of the device with the fingers thereof extending beneath the discharge opening 17 of the tube 3 from which he desires a coin or coins, and he depresses the lever arm 31 for that tube with the thumb of the same hand, and each time he depresses the lever arm 31 a coin is discharged from the opening 17 and into his hand. As each coin falls from the discharge opening 17, the rearward portion or side of the coin encounters the coin interrupting part or shelf 18 beneath the rearward part of the opening 17, thereby causing the forward portion of each coin to descend in advance of the rearward portion thereof.

Each coin interrupting part or shelf 18 is so constructed and related to its coin discharging opening 17 that it not only causes the forward portions of the coins falling from the opening to descend in advance of the rearward portions thereof but also to invert the coins and cause them to fall substantially through a vertical path down into the hand of the user of the device and to stack the coins one upon another in the hand of the user. In Fig. 5, I have shown by dot-and-dash lines several positions assumed by a coin during its descent from a discharge opening 17 to the hand of a user of the device.

I have discovered that this method of ejecting coins from a change maker not only lessens the liability of accidentally dropping coins from the hand of the user but also increases the speed of making change and

lessens the time heretofore required to acquire proficiency in using a change maker.

The rear plate 9 of the frame member 2 is provided with integral end extensions formed into vertically elongated eyes 40 in which are located the vertical members or parts 41 of hooks 42 as a means of pivotally connecting the hooks to the ends of the frame structure of the change maker. The hooks 42 are provided as a suitable means of attaching the device to the belt or other part of the wearing apparel of the user thereof.

The location of the ears or projections 14 of the connecting lugs 11 of the tubes 3, within the depression 12 in the rear plate 9 of the frame structure protects the clothing of the user of the device from the otherwise wearing effect of the ears or projections on the clothing.

Each tube 3 is provided with a suitable removable cap or cover 43 having a top provided with a slot 44 through which coins may be inserted into the tube, and provided also with a sleeve 45 surrounding the tube 3 and provided with an opening 46 therein to receive a projection 47 formed on the tube to prevent accidental displacement of the cap from the tube. When it is desired to remove the cap from the tube, the tube or cap or both may be sprung from normal condition to free the wall of the opening 46 from the projection 47.

Each lever fulcrum pin 32 is held in place and prevented from longitudinal displacement by a piece of sheet metal 49 one end portion of which is located between an arm 29 of the lever and the adjacent lug 11 of the coin tube and the other end portion of which is bent around to engage a head 50 on one end of the pin 32. By bending the part 49 from engagement with the head 50 the pin 32 may thereafter be withdrawn from the lever arms 29 and the lugs 11 for the removal of the lever. The lever arms 29 of each lever 28 embrace the two tube lugs 11 on which the lever is fulcrumed, thereby preventing lateral displacement of the levers.

I claim as my invention:

1. In a change maker, a frame structure including a coin tube and a base plate forming a support for coins within the tube and having a coin discharging opening rearwardly of the bottom of the tube, means operable to move coins rearwardly from the bottom of the tube to said opening, and a coin interrupting part terminating in a forward edge located beneath the rearward portion of said opening in spaced relation to the plane of the base plate and constructed to be encountered by the rearward portion of a coin during its descent from said opening and cause the forward portion of the coin to descend in advance of the rearward portion thereof.

2. In a change maker, a frame structure including a coin tube and a base plate forming

a support for coins within the tube and having a coin discharging opening rearwardly of the bottom of the tube, and means operable to move coins rearwardly from the bottom of the tube to said opening, said base plate having a shelf formed integral therewith and extending downwardly and forwardly beneath the rearward portion of said opening and terminating in a forward edge located beneath the rearward portion of said opening in spaced relation to the plane of the base plate and constructed to be encountered by the rearward portion of a coin during its descent from said opening and cause the forward portion of the coin to descend in advance of the rearward portion thereof.

3. In a change maker, a frame structure including a base plate, a rear plate and a coin tube having its lower end portion connected 20 to the base plate and having integral, rearwardly extending lugs connected to the rear plate; said rear plate having a forwardly pressed indentation therein, and said lugs having end portions extending through the 25 rear plate and bent laterally into the indentation therein.

4. In a change maker, a frame structure including a coin tube and a base plate forming a support for coins within the tube, the lower 30 end portion of the tube having a downwardly extending lug formed integral therewith and connecting the tube to the base plate and spacing the bottom of the tube from the base plate, and a coin ejecting mechanism including an 35 ejector plate slideable on the base plate between it and the bottom of the coin tube.

5. In a change maker, a frame structure including a coin tube and a base plate forming a support for coins within the tube, the lower 40 end portion of the tube having a downwardly extending lug formed integral therewith and connecting the tube to the base plate and spacing the bottom of the tube from the base plate, and a coin ejecting mechanism including 45 an ejector plate slideable on the base plate between it and the bottom of the coin tube, the lower end portion of the coin tube having lugs extending laterally therefrom above the ejector plate and preventing upward 50 placement thereof.

6. In a change maker, a frame structure including a coin tube, a rear plate spaced from the tube, and parts connecting the tube and the plate, and a coin ejecting mechanism having 55 an operating lever provided with laterally spaced side members embracing said parts and fulcrumed thereon, and a bifurcated spring secured to a part of the frame structure and having laterally spaced arms acting 60 against the side members of the operating lever.

7. In a change maker, a frame structure having a base plate and a coin tube rising 55 therefrom and supporting parts rearwardly of the coin tube, a coin ejecting plate slideable

between the bottom of the coin tube and the base plate, an operating lever fulcrumed on said parts and provided with laterally spaced side members operatively connected to the ejecting plate, and a bifurcated spring secured to a part of the frame structure and having laterally spaced arms acting against the side members of the operating lever.

8. In a change maker, a frame structure having a base plate and a coin tube rising therefrom and supporting parts rearwardly of the coin tube, a coin ejecting plate slideable between the bottom of the coin tube and the base plate, an operating lever fulcrumed on said parts and provided with laterally spaced side members operatively connected to the ejecting plate, a bifurcated spring comprising a connecting member and two arms extending therefrom acting against the side members of the operating lever, and a part embracing the connecting member of the spring and a part of the frame structure and securing them together.

9. In a change maker, a frame structure having a base plate and a coin tube rising therefrom and supporting parts rearwardly of the coin tube, a coin ejecting plate slideable between the bottom of the coin tube and the base plate and having a part extending upwardly from the rearward end thereof and constructed to engage the coin tube and limit the forward movement of the ejecting plate, a lever fulcrumed on said supporting parts and operable to move the ejecting plate rearwardly, and a spring acting to press the ejecting plate forwardly.

10. A frame structure for a change maker, comprising a base plate, a rear plate formed integral with the base plate, and coin tubes rising from the base plate, the tubes having integral lugs extending through the plates and bent into engagement therewith and connecting the tubes to the plates.

11. A base plate for a change maker, having a coin discharging opening therein which is provided with a coin interrupting shelf extending below the level of the body of the plate and terminating in a forward edge located beneath the rearward portion of said opening in spaced relation to the plane of the base plate and constructed to be encountered by one side portion of a coin during its descent from the opening and cause the opposite side portion of the coin to descend in advance of the first named side thereof.

12. An operating lever for a change maker, formed of a single piece of metal and comprising two spaced ejector operating arms, a part connecting the arms and from which the arms extend substantially at right angles thereto in parallel planes, and a hand operated arm projecting from one of the ejector operating arms.

13. A spring for operating a change maker, formed of a single piece of resilient metal

and comprising two spaced arms and a part connecting the arms at one end thereof, each arm having the form of an ogee curve.

14. A coin tube for a change maker, having a pair of integral lugs extending rearwardly from the body thereof in spaced relation to each other and in spaced relation to the top and bottom of the tube and constructed to connect the tube to the frame of a change maker.

15. A coin tube for a change maker, having a pair of integral lugs extending rearwardly from the body thereof in spaced relation to each other and in spaced relation to the top and bottom of the tube, and having an integral lug extending downwardly from the bottom thereof, said lugs being constructed to connect the tube to the frame of a change maker.

20. 16. A coin tube for a change maker, having integral, spaced lugs constructed to connect the tube to the frame of a change maker, and having integral lugs extending outwardly from the bottom thereof and aligned with each other and constructed to retain an ejector plate of a change maker in place.

30. 17. In a change maker, a frame structure including a coin tube and a base plate forming a support for coins within the tube, the lower end portion of the tube having a downwardly extending lug formed integral therewith and connecting the tube to the base plate and spacing the bottom of the tube from the base plate, said lug having a shoulder thereon engaging the top of the base plate and having a part extending beneath the bottom of the base plate, and a coin ejecting mechanism including an ejector plate slidable on the base plate between it and the bottom of the coin tube.

40. 18. In a change maker, a frame structure having a base plate and a coin tube rising therefrom and supporting parts rearwardly of the coin tube, a coin ejecting plate slidable between the bottom of the coin tube and the base plate, an operating lever fulcrumed on said parts and operatively connected to the ejecting plate, a bifurcated spring comprising a connecting member and two arms extending therefrom acting against the operating lever, and a part embracing the connecting member of the spring and a part of the frame structure and securing them together.

55. In testimony whereof I affix my signature.
ARTHUR F. NELSON.
